CHASER HOLDER FOR DIE HEADS

Royce M. Strickland, New Haven, Conn., assignor
to The Geometric Tool Company, New Haven,
Conn., a corporation of Connecticut

Application June 24, 1936, Serial No. 86,919

15 Claims.

(Cl. 10—104)

This invention relates to an improvement in chaser-holders for self-opening and other types of die-heads, and especially holders for thread-cutting die-heads.

5 One of the objects of the present invention is to provide superior means for holding chasers in a die-head in such a manner that the chasers may be conveniently adjusted for cutting different diameters and securely retained in given positions 10 of adjustment.

A further object is to provide superior chaser-holding means in which the chasers may be adjusted in definitely predetermined steps.

With the above and other objects in view, as 15 will be apparent to those skilled in the art from the following, considered in conjunction with the accompanying drawings, the present invention includes all features herein disclosed which are novel over the prior art.

20 In the accompanying drawings:

Fig. 1 is a view in side elevation of a self-opening die-head embodying the present invention, the operating-sleeve being partly broken away;

25 Fig. 2 is a view thereof in front elevation;

Fig. 3 is a broken sectional view taken on the line 3—3 of Fig. 2;

Fig. 4 is a similar view taken on the line 4—4 of Fig. 2;

30 Fig. 5 is a view in front elevation of one of the chaser-holders showing the chaser retired to substantially the limit of its movement into position to cut threads upon work of maximum diameter;

35 Fig. 6 is a view corresponding to Fig. 5 but with the chaser shown as adjusted to its maximum projected position for cutting threads on work of minimum diameter;

Fig. 7 is a sectional view taken on the line 7—7 of Fig. 4;

40 Fig. 8 is a perspective view of the holder-body;

Fig. 9 is a perspective view of the chaser-backing member; and

Fig. 10 is a similar view of the clamping-nut.

45 For the purpose of illustrating the present invention, there is shown in the accompanying drawings a self-opening die-head having the forward face of its body-member 20 provided with four (more or less) T-shaped guide-grooves 21, each of which is adapted to receive and guide the similarly-shaped guide-tang 22 of a reciprocating holder-body 23.

50 Inasmuch as each of the four holder-bodies 23 correspond to each other, a description of one thereof, together with its coacting parts, will serve for all.

55 The outer end of the guide-tang 22 is formed with an inclined cam-surface 24 which is adapted to be engaged by a similarly-inclined internal cam-surface 25 formed within the forward end of

a ring-like operating-sleeve 26. The said operating-sleeve encircles the body-member 20 of the die-head and is adapted to slide axially upon the same so as to act when moved forward to force the various holder-bodies 23 inwardly and to maintain the same in such position. When the said chaser-operating sleeve 26 is moved rearwardly, each of the holder-bodies 23 and the parts carried thereby will be permitted to move radially outward into their retired positions. 10 Each holder-body 23 is urged outwardly by a pair of cup-shaped plungers 27—27 (see Fig. 1), each of which is adapted to reciprocate in a suitable radial-bore 28 formed in the body-member 20 of the die-head directly back of the guide-groove 21 in the latter. Each plunger 27 is urged outwardly by a helical-spring 29 and engages with a thrust-pin 30, two of which latter project rearwardly from each of the holder-bodies 23.

20 The detailed character of the various die-heads in which the present chaser-holders may be mounted does not require detailed description beyond that already given other than to say that in the die-head shown the operating-sleeve 26 may be axially adjusted upon the body-member 20 to effect the slight advancement or retirement of the holder-bodies 23, by means of an adjusting-nut 31 mounted upon the threaded portion 32 of the shank 33 of the die-head structure.

25 The rear-face 34 of the holder-body 23 is carefully ground to provide a bearing-surface which is adapted to ride upon the front face of the body-member 20 of the die-head, as clearly illustrated in Figs. 1 and 4. In addition to being provided with the rearwardly-extending guide-tang 22, each holder-body 23 is formed with a substantially-rectangular forwardly-extending chaser-carrying post 35 having a slightly-angular disposition with respect to the said guide-tang as indicated at A in Fig. 5. The said guide-post 35 is formed in one of its sides with a guide-groove 36, and in its opposite side with a similar guide-groove 37. The edge of the end-wall 38 of the groove 36 is formed with a series of transversely-extending chaser-locating teeth 39. The said teeth 39 are preferably shaped like ratchet-teeth and have their holding-faces facing inwardly toward the center of the die-head. The said teeth 39 are adapted to be engaged by a similarly-spaced series of locating-teeth 40 formed upon the adjacent face of a wedge-shaped chaser-backing member 41 along the outer edge thereof (Fig. 9). The said chaser-backing member is formed with a guide-rib 41a which fits into the guide-groove 36 in the chaser-carrying post 35.

30 The face 42 of the chaser-backing member 41 opposite its locating-teeth 40 provides a sloping chaser-seat for the reception of a substantially- 45 50 55 60 65 70 75 80 85 90 95 100 105 110 115 120 9100 9105 9110 9115 9120 9125 9130 9135 9140 9145 9150 9155 9160 9165 9170 9175 9180 9185 9190 9195 9200 9205 9210 9215 9220 9225 9230 9235 9240 9245 9250 9

rectangular chaser 43 formed in its inner end with a series of thread-cutting teeth 44. At its outer end the chaser-backing member 41 is formed with a stop-finger 45 against which the 5 outer end of the chaser 43 bears so as to be held against outward displacement. Adjacent to its inner edge the chaser-backing member 41 is provided with a stop-flange 46 against which bears the inner side-edge of the chaser 43.

10 In order to firmly hold the chaser 43 in place upon the seat 42 of the chaser-backing member 41 and in engagement with the stop-finger 45 and stop-flange 46 thereof, the said chaser is formed with a transverse-bore 47 having a conical portion 48 at each of its respective opposite ends where it intersects the respective opposite faces of the chaser. Extending through the bore 47 in the chaser 43 is an inclined clamping-screw 49 having a spherically-contoured head 50 seated in the outermost conical portion 48 of said bore, and having a polygonal-socket 51 in its outer face for the reception of a suitable wrench.

15 The clamping-bolt 49 also extends through a clearance-bore 52 in the chaser-backing member 41 and through a clearance-slot 53 in the chaser-carrying post 35 and thence into a threaded-bore 54 in a substantially-rectangular clamping-nut 55. The clamping-nut 55 is provided on its inner face with a guide-rib 55^a fitting into the guide-groove 37 of the chaser-carrying post 35, and is adjusted longitudinally of the said groove for the purpose as will herein-after appear. In the portion of its inner face 20 most remote from the die-head body 29, the clamping-nut is formed with a series of locating-teeth 56 which are preferably of ratchet-tooth form like the locating-teeth 39 previously referred to but having their holding-faces facing 25 away from the center of the die-head. The locating-teeth 56 of the clamping-nut 55 just referred to engage with a similarly-shaped series of locating-teeth 57 formed upon the edge of the end-wall 58 of the guide-groove 37 to prevent the 30 inward displacement of the said clamping-nut 55.

25 It will be noted that the chaser-backing member 41 is of wedge-shaped form both in longitudinal and transverse section so that the chaser-seating face 42 of the said member has a compound slope with respect to its opposite face on which latter is located its guide-rib 55^a and its locating-teeth 57. That is to say, the chaser-backing member 41 has its edge which is most remote from the front face of the die-head thinner than its edge which is nearest to the front face of the die-head, as will be clearly apparent by reference to Figs. 1 and 4 in particular.

30 The slope of the chaser-seating face 42 of the chaser-backing member 41, just above referred to, serves to incline the thread-cutting teeth 44 of the chaser 43 at substantially the proper helix angle of the thread to be cut upon the work.

35 The said chaser-backing member also has its edge which is most remote from the axis of the die-head thinner than its opposite edge which is nearest to the said axis so that the chaser-seating face 42 also slopes in a direction as indicated by the broken extension lines B in Fig. 5. This tapering (B) of the chaser-backing member 41 40 in combination with the angular disposition (A) of the post 35 is designed to cause the advance edges of the thread-cutting teeth 44 of the chaser 43 to be less in advance of the center of the work when the said member is moved inwardly to correspondingly shift the chaser 43 for cutting 45

smaller diameters of work as will be seen by comparing the showings of Figs. 5 and 6.

5 It will be noted by reference to Fig. 7 in particular that the clamping-bolt 49 is inclined so that when tightened it tends to force the edge 5 of the chaser 43 which is most remote from the axis of the die-head, against the stop-finger 45 of the chaser-backing member 41, as well as serving to force the same into contact with the chaser-carrying post 35. Under these conditions 10 the chaser-backing member 41 is also urged outwardly away from the axis of the die-head but this movement is prevented, of course, by the engagement of its locating-teeth 48 with the locating-teeth 39 of the post 35. At the same time 15 that the clamping-bolt 49 is tending to force the chaser 43 and chaser-backing member 41 in the directions just referred to, it also tends, owing to the inclination referred to, to force the clamping-nut 55 inwardly toward the axis of the die-head 20 structure as well as into intimate contact with the adjacent face of the post 35. The said clamping-nut 55 is prevented, however, from moving inwardly toward the center of the die-head structure by the engagement of its locating-teeth 56 with the locating-teeth 57 on the 25 said post 35.

25 In addition to the inclination above described, the clamping-bolt 49 is also inclined so that its threaded end is closer to the front face of the 30 die-head structure than is its head 50, as will be seen by reference to Fig. 4 in particular. That is to say, when viewed from the direction indicated in Fig. 4, the clamping-bolt extends in the direction of a right angle to the inclined chaser-seat 35 41 of the chaser-backing member 41.

30 When it is desired to shift the chaser 43 inwardly toward the center of the die-head to cut threads upon work of lesser diameters than that indicated in Fig. 5, the inclined clamping-bolt 49 40 is loosened to a degree sufficient to permit both the chaser-backing member 41 and the clamping-nut 55 to be concurrently shifted inwardly the desired number of locating-teeth. During this 45 operation the clamping-bolt is permitted to move with the parts 41 and 55 relative to the chaser-carrying post 35 owing to the provision of the latter with the clearance-slot 53. After the members 41 and 55 have been moved to bring the 50 thread-cutting teeth 44 of the chaser 43 to a position nearest to the desired cutting position, the clamping-bolt 49 is tightened with the effect of firmly seating the chaser 43 against the chaser-backing member 41 and concurrently clamping the chaser-backing member 41 and clamping-nut 55 55 against the opposite sides of the chaser-carrying post 35.

55 The clamping of the parts as just above described causes the locating-teeth of both the chaser-backing member 41 and of the clamping-nut 55 to engage with appropriate adjacent locating-teeth on the said chaser-carrying post 35. If any minute adjustment of the chaser 43 is required over and above that provided by the locating-teeth on the parts 35, 41 and 55, the entire 60 chaser-holder body 23 may be appropriately adjusted in a manner usual in die-heads by just suitably turning the adjusting-nut 31 of the die-head structure.

65 Various chaser-backing members 41 may be provided to substitute one for the other when it is desired to shift to other chasers requiring a greatly different helix angle.

70 The invention may be carried out in other specific ways than those herein set forth without 75

5 departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A chaser-holder including in combination:
    - 10 a holder-body designed and adapted to be mounted in a die-head and having chaser-locating means thereon; a slide-like chaser-backing member adjustably mounted upon the said holder-body with capacity for bodily rectilinear movement toward and away from the work relative to the holder-body and having chaser-locating means engageable with the said chaser-locating means of the said holder-body; and clamping-means serving to clamp the said chaser-backing member against the said holder-body and to maintain the chaser-locating means of the said chaser-backing member in interlocking engagement with the similar means of the said holder-body.
    - 20 2. A chaser-holder including in combination:
      - 20 a holder-body designed and adapted to be mounted in a die-head and having a series of locating-teeth thereon; a slide-like chaser-backing member adjustably mounted upon the said holder-body with capacity for bodily rectilinear movement toward and away from the work relative to the holder-body and having a series of locating-teeth engageable with the said chaser-locating teeth of the said holder-body; and clamping-
      - 30 means serving to clamp the said chaser-backing member against the said holder-body and to maintain the locating-teeth of the said chaser-backing member in interlocking engagement with the locating-teeth of the said holder-body.
      - 35 3. A chaser-holder including in combination:
        - 35 a holder-body designed and adapted to be mounted in a die-head and having chaser-locating means thereon; a slide-like chaser-backing member adjustably mounted upon the said holder-body with capacity for bodily rectilinear movement toward and away from the work relative to the holder-body and having chaser-locating means engageable with the said chaser-locating means of the said holder-body; and clamping-
        - 40 means constructed and arranged to simultaneously clamp a chaser against the said chaser-backing member and the latter against the said holder-body and to clamp the chaser-locating means of the chaser-backing member into interlocking engagement with the similar means of the said holder-body.
        - 45 4. A chaser-holder including in combination:
          - 45 a holder-body designed and adapted to be mounted in a die-head and having a series of locating-teeth thereon; a slide-like chaser-backing member adjustably mounted upon the said holder-body with capacity for bodily rectilinear movement toward and away from the work relative to the holder-body and having a series of locating-
          - 50 teeth engageable with the said chaser-locating teeth of the said holder-body; and clamping-means constructed and arranged to simultaneously clamp a chaser against the said chaser-backing member and the latter against the said holder-body and to clamp the locating-teeth of the chaser-backing member into interlocking engagement with the locating-teeth of the said holder-body.
          - 55 5. A chaser-holder including in combination:
            - 55 a holder-body designed and adapted to be mount-

ed in a die-head and having chaser-locating means thereon; a slide-like chaser-backing member adjustably mounted upon the said holder-body with capacity for bodily rectilinear movement toward and away from the work relative to the holder-body and having a passage therethrough and also having chaser-locating means engageable with the said chaser-locating means of the said holder-body; and clamping-means, including a clamping-bolt extending through the passage in the said slide-like chaser-backing member and serving to clamp the said chaser-backing member against the said holder-body and to maintain the chaser-locating means of the said chaser-backing member in interlocking engagement with the similar means of the said holder-body.

6. A chaser-holder including in combination: a holder-body designed and adapted to be mounted in a die-head and having a series of locating-teeth thereon; a slide-like chaser-backing member adjustably mounted upon the said holder-body with capacity for bodily rectilinear movement toward and away from the work relative to the holder-body and having a passage therethrough and also having a series of locating-teeth engageable with the said chaser-locating teeth of the said holder-body; and clamping-means, including a clamping-bolt extending through the passage in the said chaser-backing member and serving to clamp the said chaser-backing member against the said holder-body and to maintain the locating-teeth of the said chaser-backing member in interlocking engagement with the locating-teeth of the said holder-body.

7. A chaser-holder including in combination:
a holder-body designed and adapted to be mounted
in a die-head and having chaser-locating
means thereon; a slide-like chaser-backing member
adjustably mounted upon the said holder-body 40
with capacity for bodily rectilinear movement toward
and away from the work relative to the
holder-body and having a passage therethrough
and also having chaser-locating means engageable
with the said chaser-locating means of the 45
said holder-body; and clamping-means, including
a clamping-bolt extending through the passage
in the said slide-like chaser-backing member
and constructed and arranged to simultaneously
clamp a chaser against the said chaser-backing 50
member and the latter against the said holder-
body and to clamp the chaser-locating means of
the chaser-backing member into interlocking en-
gagement with the similar means of the said
holder-body. 55

8. A chaser-holder including in combination: a holder-body designed and adapted to be mounted in a die-head and having a series of locating-teeth thereon; a slide-like chaser-backing member adjustably mounted upon the said holder-body with capacity for bodily rectilinear movement toward and away from the work relative to the holder-body and having a passage therethrough and also having a series of locating-teeth engageable with the said chaser-locating teeth of the said holder-body; and clamping-means, including a clamping-bolt extending through the passage in the said slide-like chaser-backing member and constructed and arranged to simultaneously clamp a chaser against the said chaser-backing member and the latter against the said holder-body and to clamp the locating-teeth of the chaser-backing member into interlocking engagement with the locating-teeth of the said holder-body. 60 65 70 75

9. A chaser-holder including in combination: a holder-body designed and adapted to be mounted in a die-head and having a clearance passage therethrough and also having chaser-locating means thereon; a slide-like chaser-backing member adjustably mounted upon the said holder-body with capacity for bodily rectilinear movement toward and away from the work relative to the holder-body and having a clearance passage therethrough and also having chaser-locating means engageable with the said chaser-locating means of the said holder-body; and a clamping-bolt extending through the clearance passages in the said holder-body and in the said chaser-backing member and serving to clamp the said chaser-backing member against the said holder-body and to maintain the chaser-locating means of the said chaser-backing member in interlocking engagement with the similar means of the said holder-body.
10. A chaser-holder including in combination: a holder-body designed and adapted to be mounted in a die-head and having a clearance passage therethrough and also having a series of locating-teeth thereon; a slide-like chaser-backing member adjustably mounted upon the said holder-body with capacity for bodily rectilinear movement toward and away from the work relative to the holder-body and having a clearance passage therethrough and also having a series of locating-teeth engageable with the said chaser-locating teeth of the said holder-body; and a clamping-bolt extending through the clearance passages in the said holder-body and in the said chaser-backing member and serving to clamp the said chaser-backing member against the said holder-body and to maintain the locating-teeth of the said chaser-backing member in interlocking engagement with the locating-teeth of the said holder-body.
11. A chaser-holder including in combination: a holder-body designed and adapted to be mounted in a die-head and having a clearance passage therethrough and also having chaser-locating means thereon; a slide-like chaser-backing member adjustably mounted upon one face of the said holder-body with capacity for bodily rectilinear movement toward and away from the work relative to the holder-body and having a clearance passage therethrough and also having chaser-locating means engageable with the said chaser-locating means of the said holder-body; a clamping-nut mounted upon the face of the holder-body opposite the said chaser-backing member; and a clamping-bolt extending through the clearance passages in the said holder-body and in the said slide-like chaser-backing member and into engagement with the said clamping-nut.
12. A chaser-holder including in combination: a holder-body designed and adapted to be mounted in a die-head and having a clearance passage therethrough and also having a series of locating-teeth thereon; a slide-like chaser-backing member adjustably mounted upon one face of the said holder-body with capacity for bodily rectilinear movement toward and away from the work relative to the holder-body and having a clearance passage therethrough and also having a series of locating-teeth engageable with the said chaser-locating teeth of the said holder-body; a clamping-nut mounted upon the face of the holder-body opposite the said chaser-backing member; and a clamping-bolt extending

through the clearance passages in the said holder-body and in the said slide-like chaser-backing member and into engagement with the said clamping-nut.

13. The combination with a chaser having a bolt-passage therethrough; of a chaser-holder including: a holder-body having opposite faces each provided with locating-means and also having a clearance passage intersecting each of its said opposite faces; a slide-like chaser-backing member adjustably mounted upon one face of the said holder-body with capacity for bodily rectilinear movement toward and away from the work relative to the holder-body and having a clearance passage therethrough and also having locating-means engageable with the said chaser-locating means on the adjacent face of the said holder-body; a slide-like clamping-nut engaged with the face of the chaser holder-body opposite the face upon which the said chaser-backing member is mounted with capacity for bodily rectilinear movement toward and away from the work and having locating-means engageable with the locating-means on the adjacent face of the said holder-body; and a clamping-bolt extending through the chaser and through the clearance passages in the said slide-like chaser-backing member and in the said holder-body and engaged with the said slide-like clamping-nut.

14. The combination with a chaser having a bolt-passage therethrough; of a chaser-holder including: a holder-body having opposite faces each provided with a series of locating-teeth and also having a clearance passage intersecting each of its said opposite faces; a slide-like chaser-backing member adjustably mounted upon one face of the said holder-body with capacity for bodily rectilinear movement toward and away from the work relative to the holder-body and having a clearance passage therethrough and also having a series of locating-teeth engageable with the said chaser-locating teeth on the adjacent face of the said holder-body; a slide-like clamping-nut engaged with the face of the chaser holder body opposite the face upon which the said chaser-backing member is mounted and having a series of locating-teeth engageable with the similar teeth on the adjacent face of the said holder-body; and a clamping-bolt extending through the chaser and through the clearance passages in the said slide-like chaser-backing member and in the said holder-body and engaged with the said slide-like clamping-nut.

15. A chaser-holder including in combination: a holder-body having a mounting-tang for engagement with a die-head and also having a mounting-post inclined with respect to its said tang and provided with chaser-locating means; a slide-like chaser-backing member adjustably mounted upon the mounting-post of the said holder-body with capacity for bodily rectilinear movement toward and away from the work relative to the holder-body and having chaser-locating means engageable with the said chaser-locating means of the mounting-post of the said holder-body; and clamping-means constructed and arranged to clamp the said chaser-backing member against the said holder-body and to maintain the chaser-locating means of the said chaser-backing member in interlocking engagement with the similar means of the mounting-post of the said holder-body.
